UNITED STATES PATENT OFFICE.

PAUL A. GOLINICK, OF CHICAGO, ILLINOIS, ASSIGNOR TO SPIEGEL, MAY, STERN CO., OF CHICAGO, ILLINOIS, A CORPORATION OF ILLINOIS.

LISTING ATTACHMENT FOR ADDRESSING MACHINES.

Application filed January 22, 1926. Serial No. 83,070.

This invention relates to listing machines and particularly to listing attachments for addressing machines wherein a roll of paper is fed in a step-by-step motion to the platen 5 for receiving impressions from the usual stencils which are customarily fed along a substantially horizontal guideway below the inking roller.

Listing devices of this general character usually include a supply roller from which the paper is fed to a receiving roller upon which the record strip is wound as the impressions are being made. In listing devices heretofore used for attachment to addressing machines, the supply and receiving rollers were located on respectively opposite sides of the printing mechanism and stencil guideway. In such machines, the supply roller was generally located behind the printing mechanism and the receiving roller in front of the printing mechanism on the side toward the operator, so that the paper was fed forwardly in a single strip across the guideway. Such prior constructions were complicated and the attachments generally required a mechanic to install and remove.

The main objects of this invention are to provide an improved listing attachment for addressing machines wherein the supply and receiving rollers are arranged so as to be both mounted on the same side of the printing mechanism and stencil guideway; to provide an attachment of this kind where- 35 in the rollers and operating mechanism may be mounted in front of the stencil guide- way in full view of the operator; to pro- vide improved means controlled by the movement of the printing roller for feed- 40 ing the paper strip through the machine; to provide feeding means of this kind for imparting a step-by-step rotation to the receiving roller; and to provide improved means for guiding the record strip in its 45 travel so as to cause a portion thereof to double back upon itself in the form of a bight having superposed parts arranged so that the upper part receives the impression from the stencil and shields the lower part 50 from the impression.

An illustrative embodiment of this invention is shown in the accompanying drawing, wherein:

Figure 1 is a fragmentary transverse section of an addressing machine to which an

improved listing attachment is applied, the latter being shown in elevation.

Fig. 2 is a top plan of the same, on a slightly reduced scale, and the stencils being omitted. 60

Fig. 3 is an enlarged end elevation of the listing attachment.

Fig. 4 is an enlarged detail, in section, of the feeding rollers, the view being taken on the line 4-4 of Fig. 2. 65

Fig. 5 is an enlarged detail in section of the ratchet mechanism, taken on the line 5-5 of Fig. 2.

Inasmuch as the present invention relates particularly to the listing attachment and the operating mechanism therefor, only that part of an addressing machine which is believed necessary to a complete understanding of the invention has been illustrated in the accompanying drawings. 70 75

In the form shown, the addressing machine to which the improved attachment is applied comprises a stationary frame having a horizontal table 1 on which is mounted a guideway 2 for receiving stencils 3, which are fed automatically in a step-by-step movement to the printing mechanism, which generally comprises a platen 4, impression roller 5 and distributing rollers 6 and 7. The impression roller 5 is carried at its ends 80 by arms 8 pivoted on the stationary frame and actuated by suitable power driven mechanism (not shown) for moving the impression roller alternately into engagement with the inking roller 6 and the stencil. The im- 85 proved listing attachment, to which this invention is applied, may be used in connection with various forms of machines and is not limited to the particular type herein shown. 90 95

In the specific form shown, the listing attachment comprises a frame 9, on which is mounted a pair of rollers 10 and 11 for supporting the ends of a record strip 12 which is adapted to be fed transversely of the 100 guideway 2 by an improved feeding mechanism 13.

The frame 9 may be a single casting having a base 14 and end brackets 15 and 16. The end bracket 16 is formed with arms 17 and 18 which provide journals for the rolls 10 and 11 respectively. The frame 9 is detachably secured to the table 1 by bolts 19 or other suitable fastening means and is located in front of the guideway 2 and print- 105 110

ing mechanism, so that the parts thereof are in full view of the operator.

- The rolls 10 and 11 serve as the supply and receiving rolls, respectively. Mounted on the rolls 10 and 11, are spaced collars 20 and 21, respectively, for retaining the strip in proper position. The outer collar of each roll is detachable to permit the rolls of record material to be readily inserted and removed.
- 10 The shaft of the roll 11 projects beyond its supporting bracket 16 and is provided with a pulley 22. Other storage means than that herein shown for supporting the ends of the record strip may be used if desired. In 15 some cases it may be desirable to dispense with the supporting rolls and permit the ends of the strip to rest directly on the floor or the table of the machine.

In the form shown, the roll of paper or 20 other record material is fed in strip form from the roll 10 to the roll 11. The running part of the strip rides over the base 14 of the frame 9 and extends rearwardly across the table 1 to an idler 23 around which it is 25 looped and then doubled back upon itself to form a bight of superposed parts. The bight extends through an opening in the guideway 2 and is located directly below the path of the stencils so that the upper part 30 of the bight receives the impressions from the stencil and at the same time shields the lower part from the impressions.

The improved feeding mechanism 13 includes a positively driven feed roller 24 and 35 an idler 25 arranged to grip the upper layer of the record strip as it issues from the printing mechanism and to feed it in a step-by-step movement to the receiving roller 11. The feed roller 24 is fixed on a shaft 26 40 which is journaled in the end brackets 15 and 16. One end of the shaft 26 projects beyond the bracket 16 and is provided with a ratchet 27 and a notched disk 28. Loosely mounted on the projecting end of the shaft 45 26, is an arm 29, on which is pivoted a pawl 30. The pawl 30 is normally held in engagement with the ratchet 27 by a spring 31 50 extending between the pawl and the arm 29. The arm 29 is connected to the lever 8 of the printing mechanism by a link 32, so that, upon each upstroke of the impression roller 5, the pawl 30 actuates the ratchet 27 for 55 partially rotating the feed roller 24. Co-acting with the notched disk 28, is a spring 33 60 pressed plunger 33 mounted in the base 14 for securing the feed roller 24 against any counter rotation during the return movement of the pawl. Mounted on the outer end of the shaft 26, is a pulley 34 which is connected to the pulley 22 by means of a belt 35, so that the record strip is wound upon the roller 11 as it travels from the feed roller 24.

65 The idler 25 has a shaft 36 journaled in a yoke shaped carriage 37 which is pivoted

on a shaft 38 mounted in the end brackets 15 and 16. Bearing between the carriage 37 and the base 14, is a pair of coiled springs 39 arranged to normally urge the outer end of the carriage upwardly for raising the 70 idler 25 into coacting relation with the feed roller 24. As shown in Fig. 3, one end of the shaft 36 extends through an opening 40 in the bracket 15. The outer end of this shaft projects beyond the bracket 15 for engagement with a cam or latch 41 which is adapted to urge the shaft 36 downwardly against the action of the springs 39, thereby releasing the idler 25 to permit the insertion or removal of the record strip. The opening 80 40 is sufficiently large to permit the required vertical movement of the shaft 36.

As the paper leaves the feed roller 24, it passes around an idler 42 which is journaled in the end brackets 15 and 16. Mounted on the shaft 38, is a pair of spaced collars 43 which also serve as guides for the record strip as it passes from the supply roll.

In operation, the improved listing attachment is mounted on the table 1 of the addressing machine in front of the guideway 2. The roll of record material is placed on the supply roll 10 and the other end is inserted through the guideway 2, looped around the idler 23 and then doubled back upon itself, 95 extended forwardly through the guideway and between the feed roller 24 and idler 25. The extremity of the strip is fastened to the receiving roller 11. During the operation of the printing mechanism, the lever 100 arm 8 moves the pawl 30 to actuate the feed roller 24, thereby feeding the record strip to the roll 11.

Although but one specific embodiment of 105 this invention has been herein shown and described, it will be understood that numerous details of the construction shown may be altered or omitted without departing from the spirit of this invention.

I claim:

1. A device of the class described comprising a guideway for stencils, means for feeding a record strip in a path transverse to said guideway and in close proximity to the path of the stencils, and mechanism for guiding the strip to cause a portion thereof to double back upon itself at a point adjacent said guideway whereby the doubled-over portions travel in opposite directions past said guideway with one of said portions located in position to receive an impression from the stencil and to protect the other from the impression.

2. A device of the class described comprising a guideway adapted to guide stencils along a substantially horizontal path, means for feeding a record strip in a path transverse to said guideway and directly below the path of the stencils, and guiding mechanism arranged to double the strip back upon 125 130

- itself to provide superposed parts movable in respectively opposite directions with the upper part located in position to receive an impression from the stencil and to protect 5 the lower part from the impression.
3. In a device of the class described, the combination with a stencil guideway and an impression roller, of storage means located on one side of said impression roller for supporting the ends of a record strip, means for feeding the strip in a path transverse to said guideway and in close proximity to the path of the stencils, and mechanism for guiding the strip to cause a portion thereof 10 to double back upon itself at a point adjacent said guideway whereby the doubled-over portions travel in opposite directions past said guideway with one of said portions located in position to receive an impression 15 from the stencil and to protect the other from the impression.
4. In a device of the class described, the combination with a substantially horizontal guideway for stencils, an impression roller 20 above said guideway, of storage means located on one side of said guideway for supporting the ends of a record strip, means for feeding the strip in a path transverse to said guideway and directly below the path of the 25 stencils, and guiding mechanism arranged to double the strip back upon itself to provide superposed parts movable in respectively opposite directions with the upper part located in position to receive an impression 30 from the stencil and to protect the lower part from the impression.
5. The combination with an addressing machine having a guideway for stencils and an impression roller, of a listing device comprising a supply roll and a receiving roll 35 mounted on one side of said impression roller for supporting the ends of a record strip, and mechanism adapted to double a portion of the strip back upon itself to form a bight extending transversely across the guideway.
6. The combination with an addressing machine having an impression roller and a stencil guideway, of a listing device comprising a pair of rolls located on one side of 40 said guideway for supporting the ends of a record strip, a guide located on the opposite side of said guideway and around which a portion of said strip is looped to provide 45 a bight extending transversely of said guideway.
7. The combination with an addressing machine having an impression roller and a substantially horizontal guideway for stencils, of a listing device comprising a pair of rolls located on one side of said guideway for supporting the ends of a record strip, means adapted to double said strip upon itself to form a bight extending transversely 50 of said guideway below the path of the 55 stencils, and means for feeding said strip from one of said rolls to the other to bring different portions thereof into position for receiving impressions from the stencils.
8. The combination with an addressing machine having a substantially horizontal guideway for stencils, an impression roller located above said guideway, of a listing device comprising a pair of rolls located on one side of said guideway for supporting the 60 ends of a record strip, a guide located on the opposite side of said guideway and around which a portion of the strip is adapted to be looped to form a bight extending at substantially right angles to said guideway below the path of the stencils, and means for feeding said strip from one of said rolls to the other to bring different portions thereof into position for receiving impressions from the stencils. 65
9. The combination with an addressing machine having a substantially horizontal table, a guideway on said table for guiding stencils along a substantially horizontal path, an impression roller above said guideway, a guide on one side of said guideway, of a listing device comprising a pair of rolls located on the opposite side of said guideway for supporting the ends of a record strip which is adapted to be looped around 70 said guide and to extend between the table and the path of the stencils for receiving impressions from the stencils, and means for feeding the strip in a path at substantially 75 right angles to said guideway. 80
10. The combination with an addressing machine having a substantially horizontal table, a guideway on said table for guiding stencils along a substantially horizontal path, an impression roller above said guideway, a guide on one side of said guideway, of a listing attachment comprising a frame detachably secured to said table on the other side of said guideway, a pair of rolls supported on said frame for supporting the ends of a record strip which is adapted to be looped around 85 said guide so as to be doubled back upon itself to form a bight extending at substantially right angles to said guideway with a portion thereof located 90 directly below the path of the stencils for receiving the impressions. 95
11. The combination with an addressing machine having a horizontal table, a guideway on said table for guiding stencils along a substantially horizontal path, an impression roller located above said guideway and movable into and out of engagement with the stencils, a guide located on one side of said guideway, of a listing attachment comprising a frame located on the opposite side of said guideway, a pair of rolls supported on said frame for supporting the ends of a record strip which is adapted to be looped around 100 said guide so as to be doubled back 105
12. The combination with an addressing machine having a horizontal table, a guideway on said table for guiding stencils along a substantially horizontal path, an impression roller located above said guideway and movable into and out of engagement with the stencils, a guide located on one side of said guideway, of a listing attachment comprising a frame located on the opposite side of said guideway, a pair of rolls supported on said frame for supporting the ends of a record strip which is adapted to be looped around 110 said guide so as to be doubled back 115
13. The combination with an addressing machine having a horizontal table, a guideway on said table for guiding stencils along a substantially horizontal path, an impression roller located above said guideway and movable into and out of engagement with the stencils, a guide located on one side of said guideway, of a listing attachment comprising a frame located on the opposite side of said guideway, a pair of rolls supported on said frame for supporting the ends of a record strip which is adapted to be looped around 120 said guide so as to be doubled back 125
14. The combination with an addressing machine having a horizontal table, a guideway on said table for guiding stencils along a substantially horizontal path, an impression roller located above said guideway and movable into and out of engagement with the stencils, a guide located on one side of said guideway, of a listing attachment comprising a frame located on the opposite side of said guideway, a pair of rolls supported on said frame for supporting the ends of a record strip which is adapted to be looped around 130 said guide so as to be doubled back 135

upon itself, and means controlled by the movement of said impression roller for feeding said strip step-by-step from one of said rolls to the other.

- 5 12. In a device of the class described, the combination with a guideway for stencils, of a guide on one side of said guideway, means for supporting a record strip which is adapted to be looped around said guide 10 so as to form a bight extending transversely of said guideway, a pair of coacting feed rollers located on the other side of said guideway, and means for rotating one of said feed rollers whereby the doubled over 15 portions of said strip are caused to travel in respectively opposite directions past said guideway.

13. A device of the class described comprising a supporting frame, a pair of rolls 20 on said frame for supporting the ends of a record strip, a pair of coacting feed rollers journaled on said frame on substantially parallel axes and arranged to grip the running part of the strip therebetween, mechanism for rotating one of said feed rollers 25 for feeding the strip from one of said supporting rolls to the other, and means controlled by the movement of said feed rollers for rotating said other supporting roll 30 whereby the strip is wound onto said other roll.

14. A device of the class described comprising a frame, a feed roller journaled on said frame, a movable carriage on said 35 frame, an idler journaled on said carriage and adapted to be moved thereby into and out of engagement with said roller, resilient means normally urging said carriage into position for holding said idler in coacting 40 relation with said roller, and manually controlled means for retracting said carriage and idler against the action of said resilient means.

15. A device of the class described comprising a frame, a feed roller journaled on said frame, a carriage pivoted on said frame, an idler journaled on said carriage and adapted to be moved thereby into and out of engagement with said roller, a spring 45 normally urging said carriage into position for holding said idler in coacting relation

with said roller, a manually controlled cam adapted to retract said carriage against the action of said spring for releasing said idler, and mechanism for rotating said feed roller. 55

16. A device of the class described comprising a supporting frame, a pair of rolls on said frame for supporting the ends of a record strip, a feed roller journaled on said frame, a carriage pivoted on said frame, an idler journaled on said carriage and movable thereby toward and away from said feed roller, a spring normally urging said carriage into position for holding said idler in coacting relation with said feed roller, 60 a cam adapted to retract said carriage for releasing said idler to permit the insertion of the running part of the strip between said feed roller and idler, ratchet mechanism for rotating said feed roller to feed 65 the strip from one of said rolls to the other, and means controlled by the movement of said feed roller for rotating said other roll whereby the strip is wound onto said other roll. 75

17. The combination with an addressing machine having a table, a substantially horizontal guideway on said table for stencils, a movable impression roller located above said guideway, of a listing attachment comprising a frame mounted on said table on one side of said impression roller, a pair of rolls on said frame for supporting the ends of a record strip, guiding means arranged to cause a part of the strip to double back upon itself to form a bight extending directly below the path of the stencils and transversely thereto, a feed roller journaled on said frame, an idler yieldingly mounted on said frame and movable into and out 80 of coacting relation with said feed roller, said feed roller and idler being adapted to grip the running part of the strip for feeding it from one of said rolls to the other, ratchet mechanism controlled by the movement of said impression roller for imparting a step-by-step rotation to said feed roller, and means controlled by the movement of said feed roller for rotating said other roll. 85

Signed at Chicago this 14th day of January, 1926.

PAUL A. GOLLNICK.
